SEWING MACHINE

Frank Barton, Leicester, England, assignor to
 United Shoe Machinery Corporation, Borough
 of Flemington, N. J., a corporation of New Jersey

Application February 23, 1939, Serial No. 257,989
 In Great Britain March 8, 1938

9 Claims. (Cl. 112—62)

This invention relates to sewing machines and is particularly concerned with machines for sewing together the uppers and soles of turnshoes off the last. For the sake of brevity the term 5 shoe is used herein to include outer footwear generally.

A machine of the kind with which the present invention is particularly concerned is described in the patent to Bates and Richards, No. 1,188,389, dated June 27, 1916.

The machine described in said patent is intended, as stated therein, for sewing together an upper and a felt sole, the machine having a rotary work entering horn on which the work is supported, a forked presser for pressing the work against the horn and for forming a bulge in the sole by clamping the sole between it and a convex button on the top of the horn and a curved hooked needle which, after it has penetrated the work during the formation of a stitch, is moved laterally to feed the work, the horn being lowered and the presser being raised to free the work while the work is fed.

Such a machine I have found to operate satisfactorily if the material of the sole, and it may be the upper, is comparatively firm or non-springy as the better qualities of felt and upper materials are. When the material of the sole is of an exceptionally springy nature, such as 30 soft spongy rubber or a combination of soft rubber and felt, difficulties are apt to be experienced in satisfactorily sewing together the upper and the sole in a machine having a convex horn button and a forked presser constructed in the manner described in said specification. The difficulties are apparently due, at any rate to a large extent, to different portions of the soft springy material becoming unequally and excessively bulged up between the forks of the presser during 40 the formation of successive stitches, thereby causing an uneven seam to be formed on the work.

Some types of turn shoes of the kind in which an unlasted upper and a sole are sewn together have the heel end of the sole thickened to form 45 a low heel portion and, when during the sewing of the upper and sole together this heel portion approaches the horn tip, it becomes desirable for the horn to be lowered to accommodate the extra thickness of the sole between the horn tip 50 and the presser foot.

It is one of the several objects of the present invention to provide a machine well suited for satisfactorily sewing together an unlasted upper 55 and a sole of soft spongy material as referred to.

Another object of the invention is to provide novel and convenient means whereby, in a sewing machine of the kind above indicated, the horn of the machine may be readily moved heightwise from one predetermined position to another. 5

Conveniently and as hereinafter more fully described with reference to a particular illustrative embodiment of the present invention, a curved hooked needle sewing machine having a rotary horn which is raised and lowered automatically in each cycle of operations of the machine is provided with means for adjusting the heightwise position of the horn operable during the sewing operation under the influence of an operator-controlled member to suit it for sewing, with substantially equal efficiency, the uppers of turnshoes, off the last, to their soles both around the forepart portions and around thickened heel end portions. More particularly the machine is provided with a knee lever which is 10 adapted to rotate a threaded sleeve relatively to an outer surrounding sleeve which is held relatively fixed in the frame of the machine. Rotation of the threaded sleeve serves also to raise or lower it and a horn carrying spindle is mounted 15 on this threaded sleeve in such manner that, while it may partake of the rising and falling movements of the sleeve, it does not rotate therewith. 20

In order that when the horn is in its raised 30 position and is pressing a sole against the presser foot of the machine no excessive bulging up of the material of the sole may take place, the presser foot is fixed in a convenient heightwise relation to the sewing instrumentalities and is 35 arranged to engage the sole over a relatively large area around the sewing point, thus leaving only a relatively small area to be bulged between it and the horn, and for this purpose it is of a shape like a belt buckle with a pair of spaced and parallel slots formed in it (the slots being separated by an integral cross bar) one of which slots allows the needle to pass freely through the foot on its way to pierce the work and the other of which allows the needle point to emerge through it after having penetrated through the work, the cross bar between the slots preventing undue bulging of the work between the two points where the needle enters and emerges from the work. 40

In order that the nature of the present invention may become readily apparent, the illustrative embodiment aforementioned will now be more fully described. 45

In the drawings Fig. 1 is a right hand elevation, partly in section, of the illustrative embodiment; 50 55

Fig. 2 is a right hand elevation of the lower ends of certain parts not completely shown in Fig. 1; Fig. 3 is a section taken along the line III—III of Fig. 1; Fig. 4 is a section taken mainly along the line IV—IV of Fig. 1; Fig. 5 is a diagrammatic view of a presser foot showing it in position during the sewing operation; and Fig. 6 is a plan view of said presser foot.

The machine in which the illustrative embodiment is assumed to be incorporated has sewing instrumentalities similar to those described in the patent to Bates and Richards, No. 1,188,389, above referred to.

The machine of the present illustrative embodiment has a curved work entering horn D which is somewhat similar in shape to that of the machine of said patent. This horn is secured to an outwardly extending lug 1 on a hollow sleeve member 3 which is freely rotatable about a vertical and threaded spindle 5 arranged beneath the sewing instrumentalities (including a needle N, looper L and thread finger F), the upper end of the spindle extending upwardly beyond the outwardly extending lug 1 and having an adjusting knob 7 secured thereto having a downwardly extending boss in contact with the upper end of the lug 1. Rotation of the spindle by said knob serves to adjust the heightwise setting of the horn in a manner hereinafter described. The sleeve member at its lower end rests on the upper end of a ball-bearing thrust washer 11 carried by the spindle and below this washer the spindle is threaded at 13 into the upper end of an externally threaded member 15, the threaded portion being split longitudinally to ensure a tight fit; thus by rotation of the spindle its heightwise position will be adjusted relatively to the member 15 and, by reason of the fact that it carries the washer 11 on which the sleeve member 3 rests, will cause the sleeve member to partake of its upward and downward movements.

The externally threaded member 15 is maintained in threaded engagement with an outer sleeve 17 which is supported in a vertical bearing 19 in the machine frame and is connected to the upper end of a toggle link 21 which is jointed at its lower end to the upper end of a second link 23. The lower end of this second link is connected to one arm of a bell crank lever 25, pivoted on transversely extending shaft 26, to form in effect a second toggle whilst the second arm of the bell crank lever has a block 27 secured thereto. The upper end of a treadle rod 29 passes loosely through the block and below the block carries a spring 31 on which the lower end of the block 27 rests.

During the operation of the machine, the outer sleeve 17 and the horn are automatically lowered to allow the work to be fed by lateral movement 60 of the needle when the latter is extending into the work and are raised after the feeding movement of the work by connections, indicated at 33 in Figure 1, from a cam lever 35 acting on the joint between the links 21 and 23 to cause the 65 first toggle to be broken and the horn lowered and then to cause this toggle to be straightened and the horn raised once more. In the normal initial position of the parts, the cam lever 35 and connections 33 hold this first toggle straightened but 70 the second toggle formed by the bell crank lever 25 and the link 23 is broken by means of a further spring (not shown) connected to the treadle and, therefore, the horn will be in a lowered position. Depression of the treadle is arranged to lift the 75 rod 29 and this through the spring 31 will cause

the bell crank lever to move to straighten the second toggle and thus raise the horn ready for the work to be sewn. Further upward movement of the rod is arranged to trip a clutch to set the machine into operation in which case the spring 5 31 will yield and the rod 29 pass freely up through the block 27.

Secured to and passing through the lower end of the externally threaded member 15 is a horizontally extending stud 37 and rotatably mounted on the opposite ends of the stud, at the opposite sides of the externally threaded member, are a pair of horizontal rolls 39. The rolls are received in vertical slots 41 in a member 43 which is rotatable about the vertical axis of the externally threaded member and is mounted on a bracket 45 which is L-shaped as seen from the side of the machine and secured at its extremities on the machine frame. The said rotatable member 43 is held against vertical movement on its supporting bracket and it will be understood that by rotating the rotatable member the externally threaded member 15 will be rotated and, since it is in engagement with the outer sleeve 17 which is held against movement by reason of its engagement with the treadle operated toggle links, it will also be moved upwardly or downwardly and will carry the horn with it. The threads on the externally threaded member are of coarse pitch so that a partial rotary movement 30 of said rotatable member, imparted to it by a knee lever hereinafter referred to, will effect a substantial upward or downward movement of the horn, even when the latter is being reciprocated vertically by its automatic horn drop mechanism, and the vertical slots 41 in said rotatable member will allow the horn to be raised or lowered by the knee lever or by the treadle or automatically by its horn drop mechanism during the 35 operation of the machine.

For rotating the said rotatable member 43, there is secured to the lower end thereof a pinion 47 which meshes with a curved rack sector 49 (see particularly Figure 4) formed on the forward end of a horizontally and forwardly extending lever 51 which is pivoted at its rear end, on a vertical pivot 53, to the L-shaped bracket 45. Between the pivot and the rack sector the lever is slotted, and adjustably secured in the slot is the upper end of a rod 55 having a knee 50 lever 57 secured to a lower portion thereof. Thus, by lateral movement of the knee lever 57, the rack sector 49 may be swung to the right or left of the machine and may thus impart a bodily upward or downward movement to the horn.

In order to determine, within adjustable limits, the extent of movement of the rack sector 49 and therefore the amount of heightwise movement imparted to the horn by means of the knee lever, there extends from the L-shaped bracket a horizontally extending segmental plate 59 over which the rack sector moves and this plate has spaced apart along its opposite end portions a number of vertical holes 61 adapted to receive stop pins 63, the construction being such that by inserting 65 a stop pin into a chosen one of the holes at either side of the rack sector, the extent of movement of the rack sector will be limited thereby. Furthermore, and in order to prevent undesired movements of the horn by movement of the rack 70 sector, there is secured to the undersurface of the lever 51 substantially directly below the rack sector a plate 65 having a series of teeth cut into its lower face. A spring-pressed pawl 67 arranged in the bracket 45 cooperates with adja- 75

cent teeth on the plate 65 to hold it against undesired movement but is yieldable when the lever 51 is moved by means of the knee lever 57 to allow the rack sector to move to adjust the horn. 5

5 The presser foot of the illustrative machine (shown at 69) like the presser foot of the machine described in the aforementioned specification, is bowed upwardly, as seen from the side, between its forward and rearward edges and is adapted to 10 cooperate with a button 71 on the tip of the horn D so that, when the work is pressed between the presser foot and the button, as seen in Figure 5, a projection or upward bulge in the work will be formed which the needle can completely penetrate from side to side in sewing the upper to the sole. The arrangement of the presser foot is as follows. 15 Adjustably secured by means of a horizontal slot and bolt connection (not shown) to the left hand portion of the machine is a forwardly extending bar 73 which at its forward end supports a block 75 having a pair of ears 77 receiving a pivot pin 79 on which is mounted a forwardly and rearwardly extending lever arm 81 carrying at its forward end the presser foot 69. The rearwardly extending portion of the lever arm is pivotally connected at 83 to the upper end of a small vertically extending rod 85 the lower end of which passes through the bifurcated toe portion of a downwardly extending bar 87 20 carried by the forwardly extending bar 73. A pair of nuts 89 threaded on to the lower end portion of the rod 85 and clamping the bifurcated toe portion of the downwardly extending bar 87 between them serve to determine the heightwise 25 position of the rod 85 and, since the presser foot 69 is secured to the forward end of the lever 81, consequently serve to determine the heightwise position of the presser foot and hold it fixed in whatever heightwise position it may have been 30 adjusted.

Since it is intended that a machine having the arrangement set out above shall be particularly suitable for sewing an upper to a sole of a soft spongy nature, the presser foot 69 is arranged 35 to allow only a localized bulging of the material of the sole around the sewing point and for this purpose it is given a shape, as seen in plan (see Figure 6) similar to that of a belt buckle, it being some one and a half inches square and 40 having a pair of slots 91 extending widthwise of the machine (i. e., along the direction of work feed) situated one behind the other and separated by an integral cross bar 93 which is some three eighths of an inch in extent considered 45 forwardly and rearwardly of the machine. As seen from the side, the presser foot 69 is curved upwardly between its front and rear edges to cooperate with the button 71 on the horn to form the upward bulge on the work, the button on 50 the horn actually being positioned to lie underneath the forward slot in the presser foot which slot, for this purpose, is some three eighths of an inch in extent considered forwardly and rearwardly of the machine. The rearward slot in 55 the presser foot is comparatively narrow, being three sixteenths of an inch in extent considered forwardly and rearwardly of the machine, since its purpose is merely to allow the needle to move downwardly through the foot on its way to pierce 60 the bulged portion of the work. Like the machine described in the aforementioned specification, the machine of the present illustrative embodiment is provided with means for moving the needle laterally to feed the work through the 65 machine and the slots in the presser foot are of 70 75

sufficient width, considered along the feed line, to allow the work feed to be so effected while the needle is actually in the work and portions of it are actually passing through the two slots 91 in the presser foot.

In making use of the machine as described above, the operator will first ascertain whether the presser foot 69 is correctly positioned relatively to the horn D and the sewing instrumentalities and if need be he will adjust the forward and rearward position of the same by moving the forwardly extending bar 73 forwards or rearwards or will adjust the heightwise position of the foot by loosening the two nuts 89, moving the rod 85 to swing the lever arm 81 about the pivot pin 79, and thereafter tightening up the two nuts again.

Furthermore he will ascertain if according to the thickness of the material of the sole to be sewn the initial heightwise position of the horn 20 needs adjusting and by rotating the vertical spindle 5 by means of its adjusting knob 7 he may raise or lower it relatively to the externally threaded member 15. Furthermore the stop pins 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

- position to which he swung it. It will be understood that the automatic raising and lowering of the horn is not affected by this adjustment in the heightwise position of the horn, and that the latter receives precisely the same vertical reciprocations from its cam lever when any heightwise adjustment imparted to the horn by the knee lever as it received before the knee lever was swung to effect such adjustment. After sewing all around the thickened heel portion the operator will swing the knee lever in the opposite direction and thereby raise the horn. As just above indicated, when in its lowered position, the automatic raising and lowering movements will be imparted to the horn just as when the horn is in a raised position to allow the feed of the work through the machine to be readily effected since the mechanism for effecting this raising and lowering is, as before stated, connected to the outer sleeve 17.
- The nature and scope of the invention having been indicated, and an embodiment of the several features of the invention having been specifically described, what is claimed is:
1. A machine for sewing together a shoe sole and the overlapping margin of an upper while unsupported by a last having, in combination, stitch forming devices including a needle arranged to pierce the upper and sole in a plane substantially parallel to the surface of the sole, a sole supporting horn, means acting during each stitch forming cycle to raise and lower the horn towards and from the stitch forming devices, and means under the control of the operator operable during the continued operation of the stitch forming devices in sewing a seam for adjusting the heightwise position of the horn.
2. A machine for sewing together a shoe sole and the overlapping margin of an upper while unsupported by a last having, in combination, stitch forming devices including a needle arranged to pierce the upper and sole in a plane substantially parallel to the surface of the sole, a sole supporting horn, means acting during each stitch forming cycle to raise and lower the horn towards and from the stitch forming devices, a member movable by the operator during the continued operation of the stitch forming devices in sewing a seam, and connections between said member and the horn for adjusting the heightwise position of the horn while maintaining constant the extent of the movements imparted to the horn during each stitch forming cycle.
3. A machine for sewing together a shoe sole and the overlapping margin of an upper while unsupported by a last having, in combination, stitch forming devices including a needle arranged to pierce the upper and sole in a plane substantially parallel to the surface of the sole, a sole supporting horn, a member on which the horn is mounted, a support for said member having a screw threaded connection therewith, and treadle operated means for rotating said member during the sewing operation to move the member with relation to said support and thereby vary the height of the horn with relation to the stitch forming devices.
4. A machine for sewing together a shoe sole and the overlapping margin of an upper while unsupported by a last having, in combination, stitch forming devices including a needle arranged to pierce the upper and sole in a plane substantially parallel to the surface of the sole, a sole supporting horn, a member on which the horn is carried, a sleeve supporting said member

having a screw threaded connection therewith, means acting during each stitch forming cycle to raise and lower said sleeve to move the horn towards and from the stitch forming devices, and treadle operated means for rotating said member during the sewing operation to move said member with relation to the sleeve and thereby adjust the heightwise position of the horn.

5. A machine for sewing together a shoe sole and the overlapping margin of an upper while unsupported by a last having, in combination, stitch forming devices including a needle arranged to pierce the upper and sole in a plane substantially parallel to the surface of the sole, a sole supporting horn, a member on which the horn is carried, a sleeve supporting said member having a screw threaded connection therewith, means acting during each stitch forming cycle to raise and lower said sleeve to move the horn towards and from the stitch forming devices, and treadle operated means for rotating said member during the sewing operation to move said member axially with relation to the sleeve, said means comprising a rotatable member held against axial movement and connected to rotate the horn carrying member while permitting axial movement of said horn carrying member.

6. A machine for sewing together a shoe sole and the overlapping margin of an upper while unsupported by a last having, in combination, stitch forming devices including a needle arranged to pierce the upper and sole in a plane substantially parallel to the surface of the sole, a sole supporting horn, a member on which the horn is carried, a sleeve supporting said member having a screw threaded connection therewith, means acting during each stitch forming cycle to raise and lower said sleeve to move the horn towards and from the stitch forming devices, and treadle operated means for rotating said member during the sewing operation to move said member axially with relation to the sleeve, said means comprising a rotatable member held against axial movement and mounted in axial alignment with the horn carrying member, and pin and slot connections for rotating the horn carrying member from said rotatable member while permitting axial movement of said horn carrying member.

7. A machine for sewing together a shoe sole and the overlapping margin of an upper while unsupported by a last having, in combination, stitch forming devices including a needle arranged to pierce the upper and sole in a plane substantially parallel to the surface of the sole, a sole supporting horn, a member on which the horn is mounted, a support for said member having a screw threaded connection therewith, and means for rotating said member during the sewing operation to move the member with relation to said support and thereby vary the height of the horn with relation to the stitch forming devices, said means comprising a pinion connected to said member, a rack engaging the pinion, and a treadle and connections for actuating the rack.

8. A machine for sewing together a shoe sole and the overlapping margin of an upper while unsupported by a last having, in combination, stitch forming devices including a curved needle arranged to pierce the upper and sole in a plane substantially parallel to the surface of the sole, a sole supporting horn provided with a convex sole engaging surface, a presser provided with a concave surface engaging the sole and extending across the plane of the needle between the points

where the needle enters and emerges from the sole and cooperating with the convex surface of the horn to form a bulge in the sole in the path of the needle.

- 5 9. A machine for sewing together a shoe sole and the overlapping margin of an upper while unsupported by a last having, in combination, stitch forming devices including a curved needle arranged to pierce the upper and sole in a plane substantially parallel to the surface of the sole, a sole supporting horn provided with a convex

sole engaging surface, and a presser provided with a concave surface cooperating with the convex surface of the horn to form a bulge in the sole in the path of the needle, said presser extending transversely to the direction of feed and across the plane of the needle between the points where the needle enters and emerges from the sole, and being slotted at said points to permit the passage of the needle.

FRANK BARTON. 10
